UNITED STATES PATENT OFFICE.

EDWARD LIONEL JOSEPH, OF WESTMINSTER, LONDON, ENGLAND.

OZONE GENERATOR.

Application filed July 19, 1920. Serial No. 397,365.

To all whom it may concern:

Be it known that I, EDWARD LIONEL JOSEPH, member of the Institution of Electrical Engineers and Fellow of the Chemical Society, of 96 Victoria Street, in the city of Westminster and county of London, a subject of the King of Great Britain, have invented certain new and useful Improvements in Ozone Generators, of which the following is a specification.

This invention relates to improvements in ozone generators of the general type wherein in each electrode consists of a metallic sheet (in the form of wire gauze for example) and the electrodes of a pair having opposite polarities extend in parallel planes and are separated by a sheet of dielectric material (mica, for example), whilst the stream of air, oxygen, or other gas or gaseous mixture (all of which will hereinafter be referred to as "air"), which is to be ozonized is caused to pass over the electrodes, whereof a series of pairs may be employed to act upon the stream either simultaneously or in succession. In one known arrangement of such a series of pairs of electrodes, the electrodes of opposite polarities alternate with one another in parallel planes throughout the series, a dielectric sheet being interposed between each two adjacent electrodes, whilst the air is caused to pass over all the electrodes in parallel. In another known arrangement, wherein the electrodes of opposite polarities alternate with one another in parallel planes throughout the series as before, a pair of electrodes of opposite polarities, with an interposed dielectric sheet, together constitute a separate panel which is utilized as a baffle, the panels being spaced apart and the stream of air being so directed as to follow a zig-zag course between the opposed surfaces of adjacent panels in succession, no dielectric sheet being interposed between adjacent panels.

It is to be observed that the efficiency (i. e., yield per kilowatt) of an ozone generator, more especially in cases where a highly concentrated product is required, is dependent upon the degree of intimacy of contact between the electrodes and the air

which is passed thereover during the ozonizing process. But, the closer the intimacy of contact, the greater is the necessity for passing the air as rapidly as possible over the electrodes so as to obviate an excessive rise of temperature, with consequent disintegration of the ozone produced; and the present invention has for object to provide an improved ozone generator of the general type referred to, so constructed as to permit of a greater production of ozone, relatively to the power consumed or the quantity of air passed through the apparatus, being obtained than with constructions hitherto in use.

According to the invention, the electrodes are so assembled that those of the same polarity in adjacent pairs of electrodes, extend in close superficial proximity to one another, a dielectric sheet being interposed only between adjacent electrodes of opposite polarities, whilst the assemblage of electrodes is housed within a closed container adapted to cause the air to be fed in parallel to the assemblage of electrodes and, in its passage therover, to be confined to the interstices of or between contiguous electrodes and between each electrode and the contiguous dielectric sheet, with the result that both intimacy of contact between the air and the electrodes, and also rapidity of flow of the air relatively to the quantity passed through the apparatus in a given time, are secured. In cases where a more highly concentrated product is required, a plurality of such assemblages of electrodes may be mounted within a single closed container so as to extend in substantially the same plane and thus be adapted to act in succession upon the stream of air passed through the container.

The container, which is watertight, is immersed in a cooling tank, so that the temperature of the entire contents of the container (namely, the electrode-assemblage or assemblages and the air passing therethrough) may be kept below a safe limit. Such an arrangement enables advantageous results to be secured as compared with those obtainable with a construction previously

proposed, according to which the air is led from one to another of a series of electrode-chambers in succession, by way of pipes extending through cooling tanks which alternate with the electrode-chambers.

In the accompanying drawings illustrating the invention, Figure 1 is a side elevation, partly in section, shewing a single assemblage of electrodes housed within a watertight container immersed in a water-tank. Figure 2 is a horizontal section, and Figure 3 is a vertical section, taken respectively on lines 2-2 and 3-3 of Figure 1, the space occupied by the assemblage of electrodes being indicated only diagrammatically. Figure 4 is a face view, drawn to a larger scale, of a sheet of gauze constituting an electrode superposed upon the contiguous dielectric sheet, and Figure 5 is a section of the assemblage of electrodes with their interposed dielectric sheets, taken as on line 5-5 of Figure 4. Figure 6 is a view similar to Figure 1, shewing two assemblages of electrodes housed within a single watertight container immersed in a water-tank. Figure 7 is a plan view, drawn to a smaller scale, shewing a range of containers similar to those in Figures 1, 2, and 3, mounted side by side in a single water-tank and all supplied in parallel with air and also with electric current.

Referring first to Figures 1 to 5, the assemblage of electrodes is housed in a container of sheet-metal (preferably galvanized iron) having side walls 11, 11, end walls 12, 12, a bottom 13, and an outwardly-projecting top flange 14, all preferably welded together so as to be watertight; the container, which is closed at top by a removable cover 15 (preferably of aluminium or galvanized iron), being mounted within a water-tank 10 upon the upper edge of which the flange 14 rests so as to permit of the container with its entire contents being removed from the tank when required. The tank 10 is kept charged with cold water up to a level above that of the top of the electrodes within the container, suitable means (not shewn) being provided for maintaining a circulation of water through the tank if necessary.

The removable cover 15, which is bolted to the flange 14, constitutes the upper member of a rigid rectangular frame whereof the lower member, constituted by a bar 16 (preferably of aluminum or galvanized iron) which extends near the bottom of the container, is suspended from the top member by a pair of end members 17 and 18 each constituted by a tube of galvanized iron or other suitable material which is externally threaded at its upper end to screw into a threaded hole in the cover 15 and internally threaded at its lower end to receive a screw 19 which passes through a hole in the bar 16; the frame 65 constituted by the members, 15, 16, 17, and

18 being removable as an integral whole from the container.

The right hand tube 17 (Figures 1 and 2) serves as the air inlet passage, for which purpose it is provided, above the cover 15, with a pipe connection 17^a adapted to be coupled in any convenient manner to a pipe leading from a source of air-supply, the tube 17 having one or more series of perforations 20 adapted to distribute the air evenly throughout the depth of the container, preferably towards its right hand end as indicated. Similarly the left hand tube 18 serves as the outlet passage for ozonized air, for which purpose it is provided, above the cover 15, with a pipe connection 18^a adapted to be coupled in any convenient manner to a pipe leading to the desired destination, the tube 18 having one or more series of perforations 21 adapted to collect the ozonized air evenly from the whole depth of the container, as indicated. The air may be forced or drawn through the container by suitable means as usual in ozonizing apparatus.

Within the rectangular removable frame 15, 16, 17, 18, is mounted the assemblage of electrodes, the position of which, for the sake of convenience, is only diagrammatically indicated in Figures 2 and 3. The assemblage is formed (see Figure 5) by a series of pairs of flat sheets of wire gauze (preferably aluminium) whereof the two sheets 23, 24 of a pair, constituting electrodes of opposite polarities, are separated by a dielectric sheet 25 (preferably of mica), whilst the contiguous sheets 23, 23, or 24, 24, in adjacent pairs are closely juxtaposed and adapted to serve as electrodes of the same polarity. In Figure 5, five pairs 23, 24, with their intervening dielectric sheets 25 are shewn, a similar dielectric sheet 26 being placed outside each face of the assemblage. The sheets 23, 24 of gauze are rectangular and all of the same dimensions, whilst the dielectric sheets 25 are also rectangular and all of equal dimensions but so much larger than the sheets of gauze as to leave a margin extending beyond each edge of the latter, as shewn in Figure 4. From this figure it will be seen that each corner of a sheet of gauze is rectangularly gapped to accommodate the inner corner 27^a of a rectangular distance-piece 27 interposed between the corners of adjacent sheets of insulating material, each such distance-piece 27 being constituted by a small square plate of glass or other suitable insulating material of a thickness corresponding to the thickness of the sheet or sheets of gauze lying between the correspondingly adjacent dielectric sheets.

The entire assemblage of sheets of gauze and dielectric, with their intervening distance-pieces, is rectangular in face view, and occupies, as indicated in Figures 1 and 2, only part of the distance between the

tubes 17 and 18, the spaces towards the right and left hand sides of the element being reserved for the connection of the electric conductors as hereinafter described.

5 The height of the dielectric sheets 25, 26 corresponds to the vertical distance between the cover 15 and bottom bar 16 of the frame, less the depth of a metal distance-block 28 (preferably of aluminium or galvanized 10 iron) fixed beneath the cover 15 and serving, in conjunction with the bottom bar 16, for the support of a pair of side-plates 29 of sheet-metal (preferably aluminium) of the same width as the sheets 25, 26, of insulating material, which plates 29 fit within the side walls 11, 11 of the container and are attached by screws as at 30 and 31 to the distance-block 28 and bottom bar 16 so as to leave between their inner faces a space 15 just sufficient to receive the assemblage of electrodes and to accommodate, between the outer dielectric sheets 26 of said assemblage and the side-plates 29, other and longer sheets 32 of mica or the like which extend 20 approximately the whole distance between the tubes 17 and 18 so as to serve as directors for the current of air in its passage through the container.

Between the distance-block 28 and the 30 top of the assemblage of electrodes is interposed a strip 28^a of mica or the like, which is clamped to the block 28 by a pair of blocks 33, 33, of insulating material (such as slate for example) whereby the assemblage, at its upper end, is maintained in proper position lengthwise of the container. Similarly, between the bar 16 and the bottom of the assemblage of electrodes is interposed a strip 16^a of mica or the like, 35 which is clamped to the bar 16 by a pair of blocks 34, 34, of insulating material whereby the assemblage, at its lower end, is maintained in proper position lengthwise of the container.

40 Electric alternating current is supplied to the respective gauze sheets 23, 24, of opposite polarities from cables 35, 36 attached to terminals 37, 38 housed within porcelain or other insulators 39, 40 of usual construction mounted on the cover 15 and extending through openings therein to the interior of the container between the tubes 17, 18 and the respective edges of the assemblage, the terminals 37, 38 being on the upper ends of 45 conductors 41, 42 whereof the lower ends are connected, beyond the inner ends of the insulators 39, 40, by means of wires 43, 44, to metal strips 45, 46 attached to the opposite lateral edges of the gauze sheets 23, 24 50 which serve respectively as electrodes of opposite polarities in the several pairs all the strips 45 or 46 of one polarity being clamped together at their outer ends.

It will be perceived that no part of the 60 stream of air in its passage from the inlet

tube 17 to the outlet tube 18 can avoid passing through the minute interstices of, or between, the sheets of gauze, so that the apparatus provides a very efficient means of obtaining the maximum production of ozone 70, relatively to the power consumed and to the quantity of air passed through the apparatus; it being of course understood that the rate at which the air is caused to pass must be so regulated as to obviate any tendency of the ozone to become disintegrated by remaining too long in contact with the electrodes.

When two or more assemblages of electrodes are housed within a single container, 80 they are mounted in the same plane as indicated in Figure 6, which shews two assemblages of electrodes thus mounted. In other respects the arrangement illustrated in Figure 6 is substantially similar to that described with reference to Figures 1 to 3, corresponding parts in Figures 1 and 6 respectively being denoted by similar reference numerals. The two arrangements differ, however, as regards the following de- 85 tails.

That is to say, in Figure 6 the two assemblages of electrodes are mounted at such a distance apart as to leave room between them for one of the cable-insulators, namely 95 that corresponding to the left hand insulator 40 in Figure 1; and all the electrodes of one polarity, in both assemblages, are connected to the one cable 35, whilst all the electrodes of the opposite polarity in both 100 assemblages, are connected to the other cable 36. The inter-connections are preferably such that, assuming the poles of the source of alternating current to which the cables 35 and 36 are severally connected, to 105 be at any given instant positive and negative respectively, the conductor 41 from the positive cable 35 is coupled through a wire 43 to metal strips 45 attached to one edge of all the positive electrodes in the right 110 hand assemblage, and the conductor 42 from the negative cable 36 is coupled through wires 44 to metal strips 46 attached to one edge of all the negative electrodes in both 115 assemblages, whilst one of the positive electrodes in the right hand assemblage is connected by a metal strip 47 to strips 47^a attached to one edge of all the positive electrodes in the left hand assemblage.

The water tank 10, the watertight container, the cover 15, the bottom bar 16, and the air-director sheets 32 of mica or the like, are all made of a length to accommodate the two assemblages of electrodes housed within the container, whilst the distance-block 120 28 is preferably of a length sufficient to serve, as indicated, for both assemblages in common. Each of the several assemblages of electrodes is, however, itself formed as a self-contained unit held between a separate 125 130

pair of side-plates 29, substantially in the manner described with reference to Figures 1 to 3.

In the construction illustrated in Figure 5 6, the air to be ozonized is caused to pass through the two assemblages of electrodes in succession, and it will be obvious that any greater number of such assemblages may be similarly housed in a single container so 10 as to extend in the same plane in order that the air, being caused to pass through the entire series of assemblages in succession, may be subjected to a cumulative ozonizing process, it being understood that the respective electrodes of either polarity in the several assemblages are suitably interconnected electrically.

Figure 7 shews in plan view a range of six water-tight containers each constructed 20 substantially as described with reference to Figures 1 to 3, mounted in a single water-tank 48. In this case the air inlet pipes of all the containers communicate by way of bent pipe-connections 17^a with a single air-supply pipe 49, and similarly the air outlet pipes of all the containers communicate by 25 way of bent pipe-connections 18^a with a single ozone-delivery pipe 50, the connections being arranged in parallel in such manner as to ensure the passage of equal quantities of air through the several elements. The 30 electric circuit also passes through all the elements in parallel, current being distributed to the terminals within the insulators 39 and 40 from cables 51 and 52 respectively as indicated.

It is to be observed that the improved apparatus of the present invention is adapted to enable a high efficiency to be obtained 40 with a comparatively low voltage in the secondary of the step-up transformer. This is shewn by the fact that whereas, with apparatus hitherto in use, the voltage usually required for working an ozone generator ranges, as is well known, from about 6,000 in the most favourable cases up to as much as 20,000, the apparatus of the present invention has been found to give the best results when working at a voltage of 45 about 4,000. Moreover, whereas most of the apparatus hitherto employed for the production of highly concentrated ozone require an alternating current having a periodicity of not lower than about 100 and 50 in some cases as high as 300 to 500, the apparatus of the present invention has been found capable of yielding a highly concentrated product when working with current of a periodicity as low as 25.

30 What I claim is:—

1. An ozone generator of the type referred to, wherein the electrodes are so assembled that those of the same polarity, in adjacent pairs of electrodes, extend in close 35 superficial proximity to one another, a di-

electric sheet being interposed only between adjacent electrodes of opposite polarities, whilst the assemblage of electrodes is housed within a closed container adapted to cause the air to be fed in parallel to the assemblage of electrodes and in its passage there-over, to be confined to the interstices of or between contiguous electrodes and between each electrode and the contiguous dielectric, substantially as and for the purpose set forth. 70

2. An ozone generator as claimed in claim 1, wherein a plurality of assemblages of electrodes are mounted within a single closed container so as to extend in substantially the same plane and be adapted to act 80 in succession upon the stream of air passed through the container, substantially as and for the purpose set forth.

3. An ozone generator as claimed in claim 1, wherein the electrodes housed within a single container are mounted in a frame removable at will from the container, said frame being constituted by a removable cover for the container, a bottom bar, and 90 air inlet and outlet tubes serving to connect together said cover and bottom bar, substantially as set forth. 95

4. An ozone generator as claimed in claim 1, wherein the container is made watertight and is immersed in a cooling tank, substantially as and for the purpose set forth.

5. An ozone generator comprising a plurality of electrodes arranged in pairs, each electrode consisting of a metallic sheet, a plurality of sheets of dielectric material, said pairs of electrodes extending in parallel surfaces, the electrodes of each of said pairs being of opposite polarity and being separated by one of said sheets of dielectric material, those electrodes of adjacent pairs having the same polarity extending in close superficial proximity to one another, a closed container having an inlet and an outlet, said inlet being adapted to admit air to said container so as to pass from said inlet to said outlet and in its passage to be confined to the interstices of or between contiguous electrodes and between each electrode and the contiguous dielectric sheet. 105

6. An ozone generator comprising a plurality of electrodes arranged in pairs, each electrode consisting of a metallic sheet, a plurality of sheets of dielectric material, said pairs of electrodes extending in parallel surfaces, the electrodes of each of said pairs being of opposite polarity, and being separated by one of said sheets of dielectric material, those electrodes of adjacent pairs having the same polarity extending in close superficial proximity to one another, said plurality of electrodes and sheets of dielectric material constituting a plurality of assemblages of electrodes, a closed container for said assemblages of electrodes, 110 115 120 125 130

- an inlet to said container and an outlet from said container, said inlet being adapted to admit air to said container so as to pass from said inlet to said outlet parallel with 5 said assemblages of electrodes and in its passage to be confined to the interstices of or between contiguous electrodes and between each electrode and the contiguous dielectric sheet, said assemblages of electrodes being adapted to act in succession upon the stream of air passed through said container.
7. An ozone generator comprising a plurality of electrodes arranged in pairs, each electrode consisting of a metallic sheet, a plurality of sheets of dielectric material, 15 said pairs of electrodes extending in parallel surfaces, the electrodes of each of said pairs being of opposite polarity and being separated by one of said sheets of dielectric material, those electrodes of adjacent pairs 20 having the same polarity extending in close superficial proximity to one another, a closed container, a removable cover for said container, a bottom bar, an inlet tube and an outlet tube for said container, said inlet and 25 outlet tubes serving to connect together said cover and said bottom bar and constituting with said cover and said bottom bar a frame in which said electrodes are mounted, said 30 electrodes being removable as one with said frame from said container.
8. An ozone generator comprising a plurality of electrodes arranged in pairs, each electrode consisting of a metallic sheet, a plurality of sheets of dielectric material, 35 said pairs of electrodes extending in parallel surfaces, the electrodes of each of said pairs being of opposite polarity and being separated by one of said sheets of dielectric material, those electrodes of adjacent pairs 40 having the same polarity extending in close superficial proximity to one another, said plurality of electrodes and sheets of dielectric material constituting a plurality of assemblages of electrodes, a closed container, 45 a removable cover for said container, a bottom bar, an inlet tube and an outlet tube for said container, said inlet and outlet tubes serving to connect together said cover and 50 said bottom bar and constituting with said cover and said bottom bar a frame in which said assemblages are mounted so as to extend substantially in the same plane and said electrodes being removable as one with 55 said frame from said container.
9. An ozone generator comprising a plurality of electrodes arranged in pairs, each electrode consisting of a metallic sheet, a plurality of sheets of dielectric material, 60 said pairs of electrodes extending in parallel surfaces, the electrodes of each of said pairs being of opposite polarity and being separated by one of said sheets of dielectric material, those electrodes of adjacent 65 pairs having the same polarity extending
- in close superficial proximity to one another, a cooling tank, a water-tight, closed container having an inlet and an outlet, said inlet being adapted to admit air to said container to pass from said inlet to said outlet 70 and in its passage to be confined to the interstices of or between contiguous electrodes and between each electrode and the contiguous dielectric sheet.
10. An ozone generator comprising a plurality of electrodes arranged in pairs, each electrode consisting of a metallic sheet, a plurality of sheets of dielectric material, 75 said pairs of electrodes extending in parallel surfaces, the electrodes of each of said pairs being of opposite polarity and being separated by one of said sheets of dielectric material, those electrodes of adjacent pairs having the same polarity extending in close superficial proximity to one another, said 80 plurality of electrodes and sheets of dielectric material constituting a plurality of assemblages of electrodes, a cooling tank, a single water-tight, closed container for said assemblages of electrodes, an inlet to said 85 container and an outlet to said container, said inlet being adapted to admit air to said container to pass from said inlet to said outlet parallel with said assemblages of electrodes and in its passage to be confined 90 to the interstices of or between contiguous electrodes and between each electrode and the contiguous dielectric sheet, said assemblages of electrodes being adapted to act 95 in succession upon the stream of air passing through said container.
11. An ozone generator comprising a plurality of electrodes arranged in pairs, each electrode consisting of a metallic sheet, a plurality of sheets of dielectric material, 100 said pairs of electrodes extending in parallel surfaces, the electrodes of each of said pairs being of opposite polarity and being separated by one of said sheets of dielectric material, those electrodes of adjacent pairs 105 having the same polarity extending in close superficial proximity to one another, a cooling tank, a water-tight, closed container within said tank, a removable, water-tight cover for said container, a bottom bar, an inlet tube and an outlet tube for said container, 110 said inlet and outlet tubes serving to connect together said cover and said bottom bar and constituting with said cover and said bottom bar a frame in which said electrodes are mounted, said electrodes being 115 removable as one with said frame from said container.
12. An ozone generator, comprising a plurality of electrodes arranged in pairs, each 120 electrode consisting of a metallic sheet, a plurality of sheets of dielectric material, said pairs of electrodes extending in parallel surfaces, the electrodes of each of said pairs being of opposite polarity and being 125

separated by one of said sheets of dielectric material, those electrodes of adjacent pairs having the same polarity extending in close superficial proximity to one another, said 5 plurality of electrodes and sheets of dielectric material constituting a plurality of assemblages of electrodes, a cooling tank, a single water-tight, closed container in said tank, a removable cover for said container, a bottom bar, an inlet tube and an outlet 10 tube for said container, said inlet and outlet tubes serving to connect together said cover and said bottom bar, a frame in which said assemblages of electrodes are mounted so as to extend substantially in the same 15 plane, said electrodes being removable as one with said frame from said container.

EDWARD LIONEL JOSEPH.
